ELECTRICAL SPACE HEATER

Kador George Anderson, Chicago, Ill.

Application January 31, 1947, Serial No. 725,697

8 Claims. (Cl. 219—38)

1

The present invention relates to space heaters and in particular to improvements in the construction of space heaters which use an electrical resistance unit as the source of heat.

Conventional electric space heaters may be divided into two classes; radiant heaters which depend upon the direct radiation of heat generated by an electrical resistance, and circulating or convection heaters. Circulating heaters are usually provided with a fan which moves the air rapidly over a heated element thus warming the air in the room by forced convection. Radiant heaters cause the surface of the body exposed to the glowing element to become excessively warm but heat is not transmitted to surfaces which are not exposed to the direct heat rays from the element. Electrical space heaters of the forced convection types are generally a source of discomfort to the occupants of a room in which such a heater is operated. Large quantities of air are moved past the heating element by means of the circulating fan, and this causes drafts in the room which may impair the health of small children and cause discomfort to other occupants of the room. Moreover, the high temperatures around such a heater frequently cause the fan motor to deteriorate with resulting operating difficulties.

A serious disadvantage of electrical space heaters of all types is the lack of humidifying means. The low humidity in an electrically heated room causes discomfort to the occupants and also damages the furnishings by drying them to the point that the wood and glue check and crack. Humidifiers of various types have been tried on electrical heaters but they have either been expensive or have resulted in excessive corrosion on the heating element.

The object of the present invention, therefore, is to provide a space heater which overcomes the objections of the prior art structures. As will hereinafter appear this object is accomplished by the provision of an improved circulating heater which will operate to heat and circulate the air in a room without requiring the use of a fan or other mechanical circulating device. Another object of the invention is to provide a space heater of the class described which will heat a relatively small volume of air to a high temperature, humidify the heated air, and then diffuse this heated and humidified air throughout the room in such a manner that annoying drafts will be substantially eliminated. These and other objects and advantages of the invention will be made apparent in the accom-

2

panying drawings and the following description of one preferred embodiment thereof.

In the drawings,

Fig. 1 is a perspective view of a space heater of the class described embodying the features of the present invention;

Fig. 2 is a sectional view taken on line 2—2 in Fig. 1;

Fig. 3 is a fragmentary sectional view taken on line 3—3 in Fig. 1; and

Fig. 4 is a fragmentary sectional view taken on line 4—4 in Fig. 1.

The improved heating and circulating effect attained from a space heater embodying the features of the present invention is believed to be due to the fact that the air is heated in a substantially enclosed chamber. The radiant heat from an electrical element is restricted to this confined area and does not pass to the surrounding atmosphere. The air is heated to a relatively high temperature in the enclosed space and this increases the convection effect when the heated air is vented. The high velocity of this vented air stream is utilized to draw humidified air into the heated air stream. The improved space heater as illustrated comprises a cabinet 5, a heating chamber 7 within the cabinet, an electrical resistance unit 9, disposed within the heating chamber 7, openings in the cabinet for admitting cold air to the heating chamber, a chimney 11, for venting the heated air from the heating chamber 7, and for confining the stream of vented air, means for drawing humidified air into said heated air stream, and a diffuser 13 for distributing the heated and humidified air throughout the room.

The heater cabinet 5 is desirably a vertically extending, elongated, cylindrical or prism-shaped shell 15, as is shown on the drawings. The cabinet 5 may be made of sheet material and is either formed with reinforcing type lock joints or comprises sheets bolted or riveted to a frame. A hinged door 17 is provided in one side of the cabinet 5 to allow access to the humidifying means. The cabinet structure includes a top closure 19 which is shaped as illustrated and which fits within the shell 15. The top 19 is held in position by spring clips 21 in order that it may be easily removed. The cold air inlet openings are provided by louvers or ports 23 disposed around the lower section of the cabinet shell 15. A second set of louvers or ports 25, which allow the circulation of air through the humidifier, are vertically spaced from the air intake louvers 23.

The bottom closure of the cabinet 5 is a generally square sheet metal member 27. Symmetrically disposed portions are pressed out of the bottom surface of the closures to provide four legs 29 which support the cabinet 5. Conveniently the bottom closure is attached to the shell 15 by rolling a lock joint 31 in three sides of the bottom member 27 which may be engaged by a cooperating flange 33 on the shell 15. The engaged members may be held in place by a thumb screw 35 as illustrated.

The bottom of the heating chamber 7 is made from a generally square, downwardly dished pan member 37 of sheet metal, which is adapted to fit within the cabinet 5. A plurality of turbulence rings 39 are spun or pressed into the bottom of the pan member 37. The turbulence rings 39 comprise a series of alternately concave and convex, depending concentric ridges shaped substantially as shown in the drawings. The bottom closure also serves as an added reinforcing member for the cabinet.

The top of the heating chamber is formed from a square pan member 41, similar to pan 37, and into which are formed a series of turbulence rings 43 corresponding to the lower rings 39. The upper pan 41 is vertically spaced from the lower pan member 37, substantially as shown in the drawings. A heated air vent 45, adapted to connect with the chimney 11, is located in the center of the upper pan 41.

The lower surface of the bottom pan 37 and the upper surface of the top pan 41 are covered with a suitable insulating material 47 such as a $\frac{1}{8}$ inch sheet of asbestos or the like. The interior surfaces of the heating chamber are desirably black-finished so as to provide efficient heat radiating surfaces.

A convenient method for assembling the pans 37 and 41 is illustrated in detail in Figs. 3 and 4. Indentations 49 are made in the shell 15 at the level at which the pans are to be supported. The indentations 49a for the top pan 41 are horizontally spaced from those provided for the bottom pan 37 so that notches 51 can be cut in the bottom pan 37 to allow it to slip into position. Bolts 53 are provided to maintain the pans in position on the indentations 49.

The electrical resistance unit or element 9 is disc-shaped and is provided with a series of vertical air passageways. The resistance unit 9 is horizontally disposed under the heated air vent 45 in the upper pan 41. Electrical leads 55 extend downwardly through the bottom of the heating chamber 7 where they are attached to a frame 57 provided on the bottom member 27 to support the element 9. The heating element 9 may conveniently comprise an electrical resistance wound on an insulating body which is covered by an integral metal shell. This enclosed construction obviates the danger of short circuits and shocks. Heating elements of this type are used in electric stoves, etc. and are sold under the trade name of "Calrod."

The chimney 11 extends vertically and connects the heated air vent 45 in the upper pan 41 with a point adjacent the top of the cabinet 5, as shown in the drawings. The upper portion of the chimney 11 is supported by a plurality of guide wires 59 which are attached at one end to the cabinet shell 15 and at the other end to a collar 61 encompassing the chimney. The inner surface of the chimney 11 is desirably made of a material which has a low emissivity coefficient so that the heated air will not be cooled while it is

passing through the chimney. A suitable material for this purpose has been found to be a .032-inch thick aluminum sheet.

The cabinet top 19 is provided with a flared opening 63 as is shown in the drawings. The lower portion of this opening 63 is adapted to fit loosely around the upper portion of the chimney 11 to provide an aspirating ring 65. The inverted, generally cone-shaped air diffuser 13 is supported within this flared opening by four brackets 67.

The annular air passageway 69 between the flared opening 63 and the diffusing cone 13 should be proportioned so that the total area of the passageway 69 is greater than the cross-sectional area of the top of the chimney 11. Heated air flowing from the chimney 11 will then have an unimpeded path as it passes out around the diffuser 13.

Radiating fins 71 are attached to the bottom pan member 37 of the heating chamber 7, in order to increase the transfer of heat to the air. The radiating fins 71 are vertically disposed and extend radially outwardly from the central portion of the heating chamber. The inner portions of the fins 71 are in close proximity with the heating element 9, or even may be attached to the element.

A plurality of flow-directing and radiating shells 73 are supported on the upper surface of the heating element 9 by means of wires 75 as is shown in the drawings. The shells 73 are made from sheet material and are desirably concentric cylinders or frustums of cones. The number of these shells required for optimum heat transfer varies with the size of the chimney and the temperature of the heating element; but it has been found that the air passageways between the shells 73 should be at least about 20 mm. wide. Both the fins 71 and the shells 73 should be disposed in directions which are generally parallel to the stream flow of the air in the heater so as to cause but little interference with natural convection currents.

An annular humidifier pan 77 fabricated from sheet material which is a good conductor of heat, is supported on the outer surface of the chimney 11. The central opening 79 in the pan 77, is adapted to support the pan at the desired height above the heating chamber. During manufacturing, the dimensions of the parts may be adjusted so that the humidifier pan 77 may be moved toward or away from the heating chamber 7 in order to control the rate at which the water is heated and evaporated.

Dry or unhumidified air enters the humidifying chamber through the louvers or ports 25 provided along the lower portion of the cabinet walls 15. The dry air absorbs moisture from the water provided in pan 77. The rapid passage of heated air by the aspirating ring 65 causes a pressure differential at the ring which draws the humidified air into the heated air stream.

The air to be heated has an unobstructed flow through the heater and passes along the fins and the heated convection shells which reduces the tendency of air to form an insulating film around these heating surfaces. The turbulence rings, which are one of the important features of the invention, accomplish turbulent motion of the air along the radiating surfaces and even further reduce the thicknesses of the stationary air films. The heating chamber, because of the combination of the louvers in the cabinet and the turbulence rings is substantially a "black body" and thus

transfers heat only to the air that is passing through the chamber.

By means of the heating arrangement of the invention, the air is vented rapidly enough through the chimney to cause an aspirating effect which may be used to mix humidified air with the dry heated air. The flow of air through the space heater provides adequate circulation for heating purposes, but does not cause excessive air movement in the room.

Features of my invention that are believed new are expressly set forth in the appended claims.

I claim:

1. In a space heater of the class described, a cabinet having an air vent at the upper end thereof and an air inlet port at the other end, heating means including a heating chamber, a heating element supported within said heating chamber, and a chimney disposed within said cabinet, said heating chamber having an inlet which communicates with said inlet port of said cabinet and an outlet which communicates with the inlet end of said chimney, said heating chamber having a plurality of turbulence rings formed in the upper and lower surfaces thereof, the outlet end of said chimney communicating with said air vent in said cabinet, and air diffuser means supported on said cabinet adjacent the outlet of said chimney.

2. In a space heater of the class described, a cabinet having an air vent at the upper end thereof, cold air inlet ports at the other end thereof, and humidifying air inlet ports vertically spaced above said cold air ports, heating means including a heating chamber, having a heating element supported therein, and a chimney disposed within said cabinet, said heating chamber having an inlet which communicates with said cold air inlet ports and an outlet which communicates with the inlet of said chimney, the outlet end of said chimney communicating with the interior of said cabinet, means for humidifying the air entering said cabinet through said humidifying air inlets, and means for locating the outlet of said chimney and said air vent in said cabinet so that movement of heated air out of said chimney effects a pressure differential which is operable to move air through said humidifying air inlet ports into the interior of said cabinet, and into said heated air stream.

3. In a space heater of the class described, a cabinet having an air vent at the upper end thereof, cold air inlet ports at the other end thereof, and humidifying air inlet ports vertically spaced from said cold air ports, heating means including a heating chamber, having a heating element supported therein, and a chimney disposed within said cabinet, said heating chamber having an inlet which communicates with said cold air inlet ports and an outlet which communicates with the inlet of said chimney, said heating chamber having a plurality of turbulence rings formed in the upper and lower surfaces thereof, the outlet end of said chimney communicating with the interior of said cabinet, means for humidifying air within said cabinet, and means for locating the outlet of said chimney and said air vent in said cabinet so that movement of heated air out of said chimney effects a pressure differential which is operable to move air through said humidifying air inlet ports into the interior of said cabinet, and into said heated air stream.

4. In a space heater of the class described, means defining the walls of a cabinet having an upper air vent, heating means including a heat-

ing chamber, and a chimney, said heating chamber being defined by vertically spaced upper and lower pans supported on said walls, a centrally disposed air outlet in said upper pan, said pans each including a plurality of concentric turbulence rings, air inlet ports in the walls of said cabinet intermediate said pans, a heating element located centrally in said cabinet and supported between said pans, radially disposed fins attached to said bottom pan extending outwardly from a position adjacent said heating element, said outlet in said upper pan communicating with the inlet end of said chimney, the outlet end of said chimney communicating with the interior of said cabinet and said upper air vent so as to define an aspirating ring, humidifying means disposed within said cabinet above said heating chamber, and secondary air ports in said walls of said cabinet, whereby heated air flowing through said chimney draws humidified air into said flowing, heated air at said aspirating ring.

5. In a space heater of the class described, means defining the walls of a cabinet having an upper air vent, heating means including a heating chamber, and a chimney, said heating chamber being defined by vertically spaced upper and lower pans supported on said walls, a centrally disposed air outlet in said upper pan, said pans each including a plurality of concentric turbulence rings, air inlet ports in the walls of said cabinet intermediate said pans, a heating element located centrally in said cabinet and supported between said pans, radially disposed fins attached to said bottom pan extending outwardly from a position adjacent said heating element, said outlet in said upper pan communicating with the inlet end of said chimney, the outlet end of said chimney communicating with the interior of said cabinet and said upper air vent so as to define an aspirating ring, a plurality of spaced-apart flow directing shells supported upon said heating element and disposed generally parallel to the walls of said chimney, humidifying means disposed within said cabinet above said heating chamber, and secondary air ports in said walls of said cabinet, whereby heated air flowing through said chimney draws humidified air into said flowing, heated air at said aspirating ring.

6. In a space heater of the class described, means defining the walls of an elongated, vertically extending cabinet having an upper air vent, heating means including a heating chamber and a chimney, said heating chamber being defined by a pair of generally horizontally extending vertically spaced, downwardly dished pans supported on said walls of said cabinet, said pans each including a plurality of alternately concave and convex, concentric turbulence rings, air inlet ports in said walls of said cabinet intermediate said pans, a horizontally disposed heating element located centrally in said heating chamber supported between said pans, vertically disposed fins attached to said lower pan extending radially outward from a position adjacent said heating element, a heated air outlet in said upper pan, said outlet communicating with the inlet end of said chimney, the outlet end of said chimney communicating with said air vent in said cabinet and a plurality of concentric, generally cylindrical, spaced-apart flow directing shells supported upon said heating element and disposed parallel to the walls of said chimney.

7. In a space heater of the class described, means defining the walls of an elongated, vertically extending cabinet having an air vent in

the upper end thereof, heating means including a heating chamber and a chimney disposed within said cabinet, said heating chamber being defined by a pair of vertically spaced, generally horizontally extending, downwardly dished pans supported on said cabinet walls, air inlet ports in said cabinet walls intermediate said pans for admitting cold air to said heating chamber, a centrally disposed air outlet in said upper pan, a horizontally disposed heating element, having vertically extending air passageways, supported in said heating chamber between said pans, said pans including a plurality of depending, alternately concave and convex turbulence rings, vertically disposed fins attached to said lower pans, said fins extending radially outwardly from a position adjacent said heating element, said chimney being generally vertically extending and being connected at the inlet end thereof with said air outlet in said upper pan, the outlet end of said chimney communicating with the interior of said cabinet and said air vent in a manner adapted to cause a pressure differential operable to draw air from the interior of said cabinet upon the passage of air through said chimney, a pan for containing water, disposed around said chimney, secondary air ports in said cabinet walls for supplying unhumidified air to the interior of said cabinet, and a generally conical air diffusing member disposed within said air vent adjacent the outlet of said chimney.

8. In a space heater of the class described, means defining the walls of an elongated, vertically extending cabinet having an air vent at the upper end thereof, heating means including a heating chamber and a chimney, said heating chamber being positioned adjacent the lower end of said cabinet and being defined by a pair of

generally horizontally extending, vertically spaced-apart pans which are supported on said walls of said cabinet, said cabinet walls having cold air inlet ports formed therein intermediate said pans, a horizontally disposed heating element located centrally of said heating chamber and supported between said pans, a heated air outlet in the central portion of said upper pan, said outlet communicating with the inlet of said chimney, said chimney extending upwardly and having its outlet end in communication with the interior of said cabinet and with said air vent in the upper end of said cabinet, said cabinet walls having humidifying air inlets formed therein which are vertically spaced above the upper of said pans, means for humidifying the air entering said cabinet through said humidifying air inlets, and means for locating the outlet of said chimney relative to said air vent in said cabinet so that movement of heated air out of said chimney effects a pressure differential which is operable to move air through said humidifying air ports into the interior of said cabinet and into the heated air stream.
